MANUALLY OPERATED IMPACT TOOL

Rupert F. Jackson, Cleveland, Ohio

Application January 4, 1949, Serial No. 69,200

4 Claims. (Cl. 255—42)

1

This invention relates to a manually operated impact tool particularly adapted for use in connection with stone or masonry drilling or cutting tools, such as star drills, as specifically disclosed herein, although the tool has many other uses as will be more particularly pointed out hereinafter.

The impact tool disclosed herein is in the nature of an improvement on the structure and mode of operation of the combination-tool disclosed in Patent No. 716,274, granted to C. L. Pierce, Jr. on December 16, 1902, and the primary object of the invention is to greatly increase the hitting or impact power of a hammer or plunger such as disclosed in said patent by attaching a flexible elastic or flexible means to said hammer and indirectly actuating said hammer through or by means of said elastic or flexible means.

Another object of the invention is to provide an impact tool of the aforementioned type in which the tool chuck is connected to the hammer or plunger guide or supporting rod for limited relative axial movement whereby the shock of impact is not transmitted into the guide rod, and rod handle, thereby utilizing all of the power of impact directly on the tool itself.

A further object of the invention is to provide an impact tool of the aforementioned type in which the effort or work required to be exerted by the operator, both in creating the impact and withstanding the resultant vibrations or shock, is reduced to a minimum, thereby decreasing fatigue and providing for the accomplishment of more work by the operator in a given length of time.

Other and further objects of the invention will become apparent as the description proceeds, reference being made to the accompanying drawings forming a part of the present disclosure, wherein:

Fig. 1 is a side elevational view, partly in section, of an impact tool constructed in accordance with the teaching of my invention; and

Fig. 2 is an enlarged sectional view taken along the line 2—2 of Fig. 1, looking in the direction of the arrows.

Referring in detail to the drawings, it will be seen that my impact tool comprises an elongate guide rod 1, bent at one end in the form of a loop to provide a handle 2, preferably provided with a tubular pipe 3 providing a hand grip. The loop providing the handle 2 is preferably closed and may be welded at 4 to provide a rigid structure. Preferably, the guide rod 1 is square in

cross-section, as illustrated, or non-circular in cross-section, for reasons to be presently explained, however, it may be of circular cross-section if desired.

5 A chuck, generally indicated by reference numeral 5, is connected to the other end 6 of the rod 1. The chuck 5 is larger in cross-section than the rod 1 and is provided at one end thereof with an elongate hole 7 having the same cross-sectional configuration as the rod 1 and slidably receiving the end 6 thereof. Axially elongated or oblong, opposed slots, 8 extend radially into the hole 7, and a pin 9 is press-fitted into an aperture 10 extending through the end 6 of the rod 1. The ends of the pin 9 ride in the slots 8 to limit the relative axial sliding movement between the rod 1 and the chuck 5.

When the end 6 of the rod 1 and the hole 7 are non-circular, torque forces are transmitted directly to the chuck from the rod, and hence a cotter-pin or the like may be substituted for the pin 9, if desired. When the end 6 and the hole 7 are circular, however, or otherwise shaped or dimensioned, to permit rotative movements, a more rigid connection such as the press-fitted pin 9 is preferred since such torque forces cannot then be directly transmitted but must be transmitted through the connecting pin. The non-circular connection is preferred since it substantially eliminates the breakage of connecting pins, said pins being subjected in such construction to forces not ordinarily substantially greater than those necessary to support the weight of the chuck and tool.

35 An inwardly tapered socket 11 is provided in the other end of the chuck 5 in axial alignment with the hole 7. The socket 11 receives the tapered shank 12 of the tool 13, which in this instance is a star drill, and, if desired, a set screw 14 may be provided to help retain the tool in place, although with the tapered socket and shank such screw is usually unnecessary.

The tapered socket 11 provides for the reception of tools 13 of varying sizes, and a diametrically extending opening 15 is provided through the chuck 5 forwardly of the hole 7 and in communication with the socket 11 whereby a drift may be utilized in loosening or ejecting the tool 13.

50 A tubular plunger or hammer 16 is mounted for reciprocating and preferably also rotatable movement on the rod 1 between the handle 2 and the chuck 5. The hammer 16 is provided with an axial bore 17, and closely spaced recesses 18 (only one of which is shown, in dotted

lines) are provided in the surface of the hammer substantially centrally longitudinally thereof. The spaced recesses 18 form a narrow rib 19 which is apertured as indicated at 20 to receive one end 21 of a coil spring 22 and pivotally or swingably connect the same to the hammer.

A handle 23 comprising a U-shaped guard 24 connected thereto by means of a pin 25, is pivotally or swingably connected to the other end 26 of the spring 22 by means of a substantially T-shaped bracket 27, the leg 28 of which extends through an opening 29 in the guard 24 and is apertured as indicated at 30 to pivotally receive the end 26 of the spring. It will be obvious, of course, that the ends 21 and 26 of the spring 22 will be suitably bent to maintain their respective connections.

In operation, for drilling a hole in masonry, for example, the operator positions the tool 13 at the desired location by means of the handle 2 which is held in one hand, then, grasping the handle 23, the spring 22 is elongated or stretched and the handle 23 is reciprocated through a distance which is small relative to the length of the rod 1. This reciprocating motion of the handle 23 imparts a reciprocating motion to the plunger or hammer 16 on the guide rod (which may be accompanied by a slight oscillatory movement) and as these reciprocating movements progress, the spring 22 is further and progressively elongated at the end of each stroke, thereby increasing the travel of the hammer far beyond the travel of the hand and handle 23. This action very quickly results in the impact of the forward end 31 of the hammer 16 with the rearward end 32 of the chuck 5, and the impact or hitting power developed is many, many times that which may be developed if the hand is used to directly grasp the hammer 16 as disclosed in the aforementioned patent. In addition, the effort exerted by the operator is less since the handle 23 is moved through a very short distance as compared with the length of travel of the hammer 16.

During the hitting or impacting operation just described, the tool may be oscillated or turned when desired by means of the handle 2, and a further increase in hitting power is obtained, due to the slideable connection between the guide rod 1 and chuck 5. With this slideable connection, at the time of impact, the chuck 5 and tool 13 may move outwardly relative to the rod 1, and thus very little if any of the shock of impact is transmitted into the guide rod 1 and handle 2, thereby using substantially all of the power of impact directly on the tool 13. This slideable connection, and the spring 22, also function to substantially eliminate the transmission of shock to the hands and arms of the operator, thereby further decreasing expenditure of energy on the part of the operator and further increasing his efficiency.

In the preferred embodiment of my invention, I utilize the flexible coil spring 22 to connect the handle 23 to the hammer 16, however, other flexible elastic or resilient means such as a rubber band or rod may obviously be substituted for the coil spring and swingably connected to the hammer 16 in any desired manner. Also, if a rubber band or rod is used, the handle 23 may be omitted and the end portion of such band or rod grasped directly.

Further, a flexible sling such as a chain, rawhide, or rope, may be substituted for the elastic or resilient means, if desired, such slings having a swingable connection with the hammer 16. Al-

though the impact power obtainable with such slings is somewhat less than that obtainable with elastic means, the other advantages remain substantially the same.

Although for the purpose of exemplifying my invention I have disclosed specifically herein an impact tool utilizing a star drill, it will be obvious that my impact tool has many other uses, and may be used, for example, with stone or masonry cutting chisels, wood cutting chisels and gouges, sheet metal cutters, muffler cutters, fender smoothing tools, ice chippers, nailing tools, and the like.

It may be pointed out that my impact tool may be operated with its longitudinal axis extending in any desired direction and is particularly adapted for overhead work due to the relatively short length of travel of the handle 23 required. Also, it may be used effectively to perform cutting, drilling, or other operations in smaller recesses than the tool disclosed in the above mentioned patent, for the reason that the flexible means disclosed herein requires less space for operation than does the hand and arm of the operator.

While, as indicated above, I have disclosed herein the preferred embodiment of my invention, modifications may occur to those skilled in the art, and it is my desire to cover all such modifications as come within the scope of the appended claims.

I claim:

1. In a manually operated impact tool comprising an elongate rod, a tubular hammer mounted for reciprocating movement thereon, a chuck having an axially extending hole therein receiving one end of said rod, and means connecting said chuck to said rod, an elastic means pivotally connected to said hammer and having a free end adapted to be manually grasped whereby said elastic means may be swung to actuate said hammer.

2. In a manually operated impact tool comprising an elongate rod, a tubular hammer mounted for reciprocating movement thereon, a chuck having an axially extending hole therein receiving one end of said rod, and means connecting said chuck to said rod, a coil spring pivotally connected to said hammer, said coil spring having a free end, and a handle pivotally connected to said free end of said coil spring and adapted to be manually grasped whereby said coil spring may be swung to actuate said hammer.

3. In a manually operated impact tool comprising an elongate rod and a tubular hammer mounted for reciprocating movement thereon, a chuck having an axially extending hole therein receiving one end of said rod, an elongate slot in said chuck extending radially into said hole, a pin of lesser diameter than the length of said slot secured to said one end of said rod and extending into and slideable within said slot for connecting said chuck to said rod for relative limited axial sliding movement, and an elastic means pivotally connected to said hammer and having a free end adapted to be manually grasped whereby said elastic means may be swung to actuate said hammer.

4. In a manually operated impact tool comprising an elongate rod and a tubular hammer mounted for reciprocating movement thereon, a chuck having an axially extending hole therein receiving one end of said rod, an elongate slot in said chuck extending radially into said hole, a pin of lesser diameter than the length of said slot secured to said one end of said rod and ex-

tending into and slidable within said slot for connecting said chuck to said rod for relative limited axial sliding movement, and a coil spring pivotally connected to said hammer, said coil spring having a free end, and a handle pivotally connected to said free end of said coil spring and adapted to be manually grasped whereby said coil spring may be swung to actuate said hammer.

RUPERT F. JACKSON.
